ADJUSTABLE WEB FEED DEVICE FOR LABEL CUTTING AND FOLDING MACHINES

Arthur F. Bardsley, Rocky River, and Kenneth W. Reed, East Cleveland, Ohio

Application July 14, 1948, Serial No. 38,716

3 Claims. (Cl. 271—2.1)

1

This invention relates to improvements in label cutting and folding machines, that is to say machines for severing fabric labels one by one from a long strip, the insignia of each label being generally woven into the strip. After a label is severed the cut edges are folded over, so that the label is then ready to be sewed to the garment to which it is to be attached. The strip of labels is supplied to the garment manufacturer in a roll which is mounted in the machine and from which the strip is fed by a crank and ratchet mechanism, or other means for imparting step by step movement.

One of the objects of the invention is the provision of a machine of the character stated having a minimum number of parts requiring a minimum amount of servicing.

Another object is the provision in such a machine of means for adjusting the strip feeding means during the operation of the machine.

Another object is the provision of a machine of the character stated which is adapted to handle labels of a wide range of sizes.

Another object is the provision of means for automatically interrupting the operation of the machine whenever a greater than ordinary thickness of strip material approaches the cutting knife.

Other objects and features of novelty will appear as we proceed with the description of that embodiment of the invention which, for the purposes of the present application, we have illustrated in the accompanying drawings, in which

Fig. 1 is a side elevational view of a machine embodying the invention.

Fig. 2 is a plan view of the same.

Fig. 3 is an end view partly in section on the line 3—3 of Fig. 1.

Fig. 4 is a view in plan of a fragment of a label strip such as the machine is adapted to handle, and

Fig. 5 is a view of a severed label with folded end edges as delivered from the machine.

In the drawings 10 refers to the side members of the machine frame which may have suitable transverse members, some of which are indicated at 11, 12, 13 and 14. Brackets 15 at the rear ends of the frame side members rotatably support a shaft 9 which carries a roll 16 of label strip material. The strip S taken from the roll 16 with its face side down passes diagonally upward over the surface of a feed roll 17 which is mounted on a shaft 18 journaled in the sides of the frame. Shaft 18 is driven clockwise, as viewed in Fig. 1, a partial revolution at a time

2

by means of a crank and ratchet or overrunning clutch drive, the outer element of which is indicated at 19 and the inner element at 20. The crank is shown at 21, connected to the outer element 19. A connecting rod 22 pivoted to the outer end of crank 21 leads down to a pivot 23 projecting from a nut 24 which is mounted to slide in a guide frame 25 that is rigidly carried on one end of a shaft 26 journaled in the side members 10 of the frame. This shaft may be driven by any suitable means as from an electric motor, not shown, as for example by means of a belt 27 running over a pulley 28 keyed to the shaft and over a pulley, not shown, driven through reduction gearing by the motor shaft.

In the guide frame 25 there is journaled a screw shaft 30 which cooperates with nut 24 and serves to shift that nut radially inward or outward as the screw is turned in one direction or the other. The throw of the crank to which connecting rod 22 is pivoted is thereby adjustable. On the outer end of screw 30 externally of the guide frame 25 there is a head 31 pinned to the screw shaft, having a series of radially projecting pins 32.

A handle 33 is pivoted at 34 to a bracket 35 mounted upon or forming part of the frame of the machine. A fork 36 is rigidly attached to the handle 33 at its pivoted end, and comprises two arms 37 which normally straddle the pins 32 without touching them. Handle 33 extends through the machine to the operator's side thereof. When it is swung a short distance to either side of the illustrated position one of the arms 37 is brought into position to be contacted by a pin 32 as the head 31 moves upwardly during each clockwise revolution of the crankshaft 26. In this way the screw 30 may be turned in either direction, advancing the nut 24 a very small fraction of an inch toward or away from the axis of the crankshaft. Swinging the handle 33 back to the illustrated position causes the arms 37 to clear the pins 32 and leave the screw undisturbed on succeeding revolutions of the crankshaft.

To hold the label strip S against the surface of feed roll 17 and give the latter proper traction against the strip, we cause a roller 39 to run upon the strip over the top of the feed roll. Roller 39 is mounted upon the free ends of a pair of bars 40 which may be joined by a cross brace 41, and are mounted at their rear ends upon pivots 42 carried by the frame. By making the roller 39 sufficiently heavy it may be caused to press against the strip S with sufficient force to give

the roll 17 proper traction, although obviously this force may be augmented by suitable spring means if desired.

In a bracket extending inwardly from one of the bars 40 there is threaded a small screw 44 which is adjusted to clear a trigger 45 projecting downwardly from a limit switch 46 which is attached to the frame member 10 by any suitable means. In the event that a thickness in the strip material is greater than the regular thickness of the strip, for example a splice especially where the two parts are pinned together, the roller 39 will rise sufficiently to cause screw 44 to trip trigger 45, opening the limit switch. With the motor circuit passing through switch 46 therefore, the machine will immediately stop and the obstruction in the strip which might otherwise cause harm to the shearing knife or the folders may be removed and the machine restarted. The restarting is effected by means of a button 47 projecting upwardly from the housing of switch 46. Depressing this button closes the switch and sets the trigger 45.

The strip S after passing between feed roll 17 and traction roller 39 is pushed forwardly over a plate 48 flush with the top of roll 17. It then travels over a narrow plate 50 flush with plate 48 and carried by frame member 14 and a stationary knife blade 49 onto a plate 51 flush with plates 48 and 50, and over that plate onto a second narrow plate 52 carried by frame member 13. Plate 51 forms part of a transversely slidable table, being attached to a panel 53 provided with tongues 54 along its side edges which take into correspondingly shaped grooves in the frame members 13 and 14, whereby the table 51, 53 is slidably guided for movement transverse to the path of movement of strip S.

Narrow plates 50 and 52 extend transversely beyond the main frame of the machine, where they are provided with curved overhanging edge folders 54 of more or less conventional form. In a pair of frame brackets 55 and 56 there is rotatably mounted a shaft 57 which carries a pair of pressing rollers 58 that are disposed in the same vertical planes with the outer ends of folders 54. On one end of shaft 57 there is a pulley 59 (see Fig. 2) over which runs belt 60 that extends down and around a pulley 61 on a shaft 62 that is journaled in bearings carried by brackets extending outwardly from the frame of the machine. Idler rollers 63 on a shaft 64 are positioned directly above rollers 58, shaft 64 being rotatably mounted in the outer ends of a pair of arms 65 arranged to swing on pivots 66 mounted on the frame. Arms 65 are strongly biased downward by tension springs 67.

70 is an L-shaped bracket carried by the frame and having a bearing for a trunnion 71 which carries a shearing arm 72 upon which is mounted a cutting blade 73 that cooperates with an edge of the fixed blade 49 for severing the foremost label from the strip S. An operating rod 74 extends downwardly from the arm 72 loosely through a hole in a frame projection 75 down to a pivot 76 carried by a triangular plate 77 which is pivoted at 78 to the frame and carries a roller 80 that runs upon a cam 81 fixed to camshaft 26. Between projection 75 and a collar 82 pinned to the rod there is a coil spring 83 which imparts a downward motion to the rod and a shearing action to blade 73 whenever the low spot of cam 81 engages follower 80. The movable blade is held in cutting relation with the fixed blade by a spring 85 which bears at one end against

bracket 70 and at the other end against an adjusting nut 86 mounted on the threaded end of trunnion 71 and held in adjusted position by means of a lock nut 87.

Provision is made for clamping the end label of the strip to the transversely movable table 51, 53. This clamping means may include two side members 90, each of which has a top flange 91, a pair of inwardly extending ears 92 and a short bottom flange 93, the latter being secured to the table by screws or the like 94. In the ears 92 and flange 91 of each of these side members 90 posts 95 are slidably mounted, and fixed to the posts there is a cross bar 96. At the lower ends of each pair of posts 95 there is a clamping shoe 97 biased downwardly by the compression springs 98 surrounding the posts between the arms 92 and the shoe 97. These springs tend to depress the shoes into clamping position. A rock shaft 100 is rotatably mounted in the two members 90. It carries a pair of cams 101 each having a flat surface 102, the cams being disposed beneath the cross bars 96. When the circular surfaces of the cams engage the cross bars 96 the latter are raised against the action of springs 98. When the cams are turned however to cause the flats 102 to engage the cross bars the latter are lowered and the clamping shoes are depressed by the springs 98. A hub 103 is pinned to shaft 100, and from this hub an operating pin 104 extends radially.

The transversely movable table is operated by means of a pair of links 105, a lever 106 pivoted to the frame at 107 and a roller follower 108 running upon a cam 109 fixed to shaft 62. To the lower end of lever 106 beneath its pivot 107 there is attached a tension spring 110, the opposite end of which is attached to the frame. Spring 110 moves the table outwardly, while cam 109 returns it to initial position.

On shaft 62 there is a second cam 111 cooperating with a follower 112 on the lower arm of a lever 113 pivoted to the frame at 114. Follower 112 is held against the cam by tension spring 99 attached at its ends to the frame and to lever 113. The upper end of that lever is pivotally connected to a slidebar 115 which runs in a guide 116 on bracket 70. Bar 115 carries two pins 117 and 118 which are adapted to engage pin 104 to throw it from clamping to unclamping position and vice versa.

Shaft 62 is driven from shaft 26 by means of spiral gears 119 and 120 of equal size. In order to put a braking action upon roll 16 and keep it from unwinding faster than required by the feed roll, we employ a roller 121 bearing on the surface of roll 16, roller 121 being keyed to a shaft 122 which is carried in a pair of swingable arms 123. To prevent roller 121 from turning freely and keep the strip S under slight tension there is fixed to shaft 122 a wheel 124 over which extends a brake band 125 that is maintained under tension by a coil spring 126.

Operation.—For each revolution of the crank-shaft 26 the feed roll 17 will be driven forward through a certain angle, and in cooperation with the traction roller 39 will feed the strip S forward a distance equal to the distance between cuts, this distance being indicated by the broken lines in Fig. 4. At the time the feed takes place the table 51, 53 is in its initial position illustrated in Fig. 3, the knife 73 is tilted upwardly out of the way and the clamping shoes 97 are raised. The forward end of the strip S therefore readily 75 slides over the table to the position which it

should occupy when the knife descends. Cam 111 and spring 99 then function to pull slide bar 115 to the right, as viewed in Fig. 3, causing the pin 117 to swing pin 104 over center to bring the flat part 102 of cams 103 into position under cross bars 96, when the shoes 97 are forced down into clamping position by the springs 98. The forwardmost label of the strip S is thereby clamped to the table somewhat inwardly of the end edges of the label. Cam 81 and spring 83 then function to draw the shearing knife down, severing the end label from the strip. Immediately after the cut is made the low spot of cam 109 runs under follower 108 and spring 110 rocks lever 106 to the right as viewed in Fig. 3. The severed label is thereby shifted transversely and its edges are turned over by the folding cams 54. The movement of the table continues until the folded edges of the label pass into the bite of the press rollers 58, 63 which operate under appreciable pressure to crease the folds. If desired one or both of the rollers 58 and 63 of each pair may be heated electrically or otherwise, but inasmuch as such means forms no part of the present invention it is not illustrated in the drawings. As soon as the label edges are gripped by the pressing rollers, pin 104 strikes pin 118 on bar 115 and the cams 103 are turned to the Fig. 3 position, thereby unclamping the severed label, which is then drawn off the table by the pressing rollers at the same time that they impart the desired creases to the folds. At about that time the follower 108 on lever 106 rides out of the low spot of cam 109 onto the high portion of the cam, which swings lever 106 toward the left and thereby returns the table 51, 53 to its initial position in preparation for the next cycle of the machine.

As the operation of the machine progresses, if the length of the individual labels should vary somewhat the operator by manipulation of handle 33 may readily change the throw of the adjustable crank on crankshaft 26 to increase or decrease the length of feed by a small fraction of an inch, when the handle is again returned to its intermediate position. If at any time a splice in the strip thick enough to interfere with the proper operation of the machine rides under the traction wheel 39, adjustable screw 44 operates trigger 45 to open the limit switch and stop the motor. The operator then removes the pin by which the strip ends are held together, takes out the small length of strip in advance of the splice and draws forward the new length into proper position, after which he depresses push-button 47 to again start the motor and reset the limit switch.

The width of the side roller 17 is sufficient to accommodate a label strip of maximum width. In every case the left edge of the strip, facing forwardly in the direction of travel, is disposed as shown in Fig. 2. The transverse travel of the table 53, 51 is sufficient to cause the left edge of the severed label to pass through the folders and enter the bite of the pressing rollers 58, 63. Whatever the width of the strip may be its cut edges are thus completely folded and pressed and it is drawn off the table and delivered at the side of the machine.

The dimensions of plates 51 and 52 in the direction of feed are selected for a label strip having labels of a given length. For labels of a longer length this dimension of plate 51 is increased and that of plate 52 is correspondingly decreased. For labels of shorter length the same dimension of length 51 is decreased and that of plate 52 increased. By means of this simple change along with the required change in the drive of the feed roller 17 labels of a wide range of sizes may be handled.

Having thus described our invention, we claim:

1. In a machine of the character described, a frame, oscillatable means arranged when moving on the forward stroke to advance a strip, the return stroke being idle, a power driven rotary crank, a connecting rod pivoted to said crank and to said oscillatable means, screw and nut means for varying the effective length of said crank, the screw of said screw and nut means having outwardly extending projections, and means on said frame settable into the path of said projections on either side of said screw adapted to engage said projections whereby the length of feed may be adjusted during operation of the machine.
2. In a machine of the character stated, a frame, strip feeding means carried by said frame comprising an intermittently acting feed roller, a ratchet drive for said roller having an operating arm, a connecting rod pivoted to said arm, a power driven rotating crank pivoted to the opposite end of said rod, screw and nut means for varying the effective length of said crank, the screw of said screw and nut means having outwardly extending projections, and means on said frame settable into the path of said projections on either side of said screw for imparting a partial rotation to said screw in either direction, whereby the length of feed may be increased or decreased during operation of the machine.
3. A machine as defined in claim 2, wherein the said screw has a head and said projections consist of pins extending radially from said head and said settable means comprises two arms straddling the path of said head and shiftable to cause either arm to move into the path of said pins for engagement with a pin as the crank revolves.
